UNITED STATES PATENT OFFICE.

WILLIAM H. DAVIDSON, OF BOSTON, MASSACHUSETTS.

STRAP-FASTENER, &c.

No. 918,829.

Specification of Letters Patent.

Patented April 20, 1909.

Application filed March 23, 1908. Serial No. 422,766.

To all whom it may concern:

Be it known that I, WILLIAM H. DAVIDSON, a citizen of the United States, residing at the city of Boston, in the county of Suffolk and State of Massachusetts, have invented new and useful Improvements in Strap-Fasteners, &c., of which the following is a specification.

This invention relates to strap-fasteners of that class which are to be used with, and on straps in strapping packets, trunks, boxes and such like, and which are adapted to secure, so far as may be possible, a strap placed around all the several sides of a packet, etc., against accidental displacement, and, preferably, also to secure it against surreptitious removal from its position around and hold upon the packet, etc.

The principal object of this invention is to produce a fastener of the class stated, which is simple in construction, easily manipulated, and capable of permitting a strap to be most readily and in a continuous length placed around all the several sides of a packet, etc., and for each section or portion of the strap so placed to be readily engaged with the fastener, and engaged, made secure against accidental detachment, as also, preferably, secure against surreptitious removal from the fastener and from the packet, etc., and in all respects and so far as may be practicable to obtain an absolute secure fastening and holding of the strap on the packet, etc., and one such, that the strap can only be released by a proper manipulation of it and of the fastener, or by a severing either of the strap or fastener.

The object above stated is most successfully and practically secured by a strap-fastener of this invention, and which is to be now described, in detail, reference being had to the accompanying drawings.

In the drawings, Figure 1 is an isometrical view of a packet and of a strap encircling it on all of its several sides, and a fastener of this invention securing said strap, in its so-encircling position, to the packet. Fig. 2 is a plan view of the fastener and at its face or side which is outermost when the fastener is in use. Fig. 3 is a cross section on dotted line 3—3, Fig. 2. Fig. 4 is a cross section on dotted line 4—4, Fig. 2. Fig. 5 is a plan view similar to Fig. 1, but in detail, as will hereinafter appear. Figs. 6 and 7 are respectively plan and side views of the fastener, and of means for securing its several parts

together and to the strap engaged therewith. Fig. 8 is a plan view of the fastener on a reduced scale from that of the preceding figures, and illustrating a modification thereof as hereinafter appears.

In the drawings, Fig. 1, A is a packet of rectangular shape on all its several sides, and B is a strap encircling all of said several sides and secured in such position by means of a fastener common to the several so running lengths or sections of said strap.

The fastener, in accordance with the main feature of this invention, consists, essentially, of a skeleton or primary-frame of metal, or other suitable material, which is substantially flat on both its upper and lower sides, (Figs. 2, 3, 4, 5, 6, 7 and 8) and of a secondary plate or frame of metal, or other suitable material. This secondary-frame along one edge is hinged to one edge of said primary-frame, and it is adapted to be closed on and opened from the same (Figs. 2, 3, 4, 6, 7 and 8) and it and said primary-frame have means, hereinafter described, relatively constructed and adapted for cooperative action so as to enable said frames to be bound and secured together, when closed the one upon the other, as before stated, and to be released when to be opened from each other.

The primary-frame, as particularly shown, Fig. 5, has, at one side, a bar G which is preferably cylindrical and straight, and along its inner edge it has a rectangular opening or slot D. The primary-frame also has along two of its sides and each in continuation of an opposite end of said bar C, two bars E and F, each of which, preferably, is curvilinear in outline from end to end, both on the inner and outer edges, (concave on the inner and convex on the outer). Along the inner edge of each bar E, F, there is an opening G and H, respectively. These two curvilinear bars E, F, at their respective ends the farther from the bar C, join and form the remaining side J of the frame, and the outer edge of this side J, from end to end, is, preferably, convex, and the inner edge of said side J is concave from end to end and said side J is joined to the side of the frame having the bar C and the slot D, by means of a central piece or bar K, which is at a right angle to said bar C and also has its outer edges a and a² more or less straight and parallel.

The central bar K has an elongated and preferably, oval-shaped opening L, and this

opening is substantially at the central portion of the primary-frame taken as one whole, and its longer axis is substantially parallel to the straight edges a , a^2 of the bar K.

- 5 The side-bar E of the primary-frame, Figs. 5 and 8, is in one piece with, or fixed in position as to the other parts of said frame, and, Figs. 2, 3, 4, 6 and 7, it is a separate piece from the rest of the frame, which at that side 10 is open, and as a separate piece it is, at one end, held and hung on a fixed upward projecting pin M of, and located on the frame adjacent to its side-bar C, and, at the other end, it has a slot N having an enlargement at one 15 end, and all suitable for said pivoted side-bar, by such slot, to be set over a fixed upward projecting headed and shouldered-pin O of the frame at its side J, (Figs. 2, 3, 4, 6 and 7) and so, as is plain, the side-bar E of 20 the primary-frame can be attached at its end having the slot N to the headed-pin O of the frame thus completing said frame and it can be detached from said headed-pin and being then free can be swung away from the other 25 parts of the frame, (see Fig. 2, dotted lines,) all as and for the purposes as will hereinafter appear.

The secondary-frame consists of a plate P which along one of its sides has a tubular-hub P² and by this hub it is hung on a fixed horizontal axle P³ which is located on the primary-frame at and along its side, and above the cross-bar C, (Fig. 3), and thus the secondary-frame, by swinging it on said axle, can 30 be placed directly upon the primary-frame, (Figs. 2, 3, 4, 6 and 7) and so put in position to cover the same, as for illustration, the central bar K in whole and also the side-bars E and F and the side-bar J joining them as has 35 been described, nearly for their full width, Figs. 2, 3, and 4. Or as shown, Fig. 6, said secondary-frame may be sized and shaped at its outer edge so that when closed upon the primary-frame to cover said bars E, F, only 40 in part. Further, the secondary-frame, preferably, is dish-shaped, as at P⁴, Figs. 3 and 4, and again, preferably, its hub P², at its under portion and which is toward the primary-frame, has an eccentric periphery P⁵, Fig. 3, 45 so that as the secondary-frame is swung to close it, and it is in a closed position on the primary-frame, as described, it will press and bind on the cross-bar C of said primary-frame, or on whatever may be about said bar, as for 50 instance, a portion of the strap B, as will hereinafter appear.

The means for holding the secondary-frame P in its position covering the primary-frame, comprise, in substance, a button-head Q of corresponding shape and size to the elongated-opening L in the cross-bar K of said primary-frame, and thus said head Q properly placed can pass into and out through said opening L; an axial-pin R, to 55 which, at its inner end, said button-head is

axially attached, and which, at its outer end is carried by and is free to turn on said cover or secondary-frame P, and a radial arm S, Figs. 6, 7 and 8 which, at one end, is attached to the outer end of said axial-pin R, 70 or in place of said arm S, of a lock-mechanism of any well known and suitable kind may be used. If a lock-mechanism is used, it with the axial-pin R are to be arranged within a boxing or casing T, in turn attached 75 to the under or inner side of the secondary-frame P, and this boxing is to have a key-hole U for the insertion of the key to work on the lock-mechanism, and through it to turn said axial-pin R, and therethrough to 80 swing the button-head Q which it carries, in the one instance, so as to unlock it, and when unlocked to have said button-head in proper position to pass through the elongated opening L of the cross-bar K of the 85 primary-frame, and when locked to have said button-head extending, by its longer axis, across said elongated opening L and in the direction of its shorter axis.

The arm S, preferably, is of sufficient 90 length by its free end S² to bear on the upper side of cross-bar C of the primary-frame when it is swung in the proper direction therefor, and that is, when it is swung so as to bring the button-head Q by its longer axis 95 across the opening L in the direction of its shorter axis, and again to add efficiency to the pressure of said arm S on said bar C, said arm may be bent along its length, Fig. 7, and further may have more or less resiliency.

In Fig. 8 the outer edge of the secondary-frame P, is shown as having teeth V, and said outer edge lies slightly within the inner edge of the side-bars E and F of the primary-frame, when the frame P is closed, and again, the secondary-frame P has a handle W for convenience in raising it from the primary-frame.

In all forms of combination of parts and 110 shape of the two frames, the primary and the secondary, shown in the drawings and hereinbefore described, the holding together of the two frames is secured by swinging the button-head Q so that it will be placed by its 115 longer axis across the opening L of the central bar K of the primary-frame, and so that it will then be or extend in the direction of the shorter axis of said opening, and in this position of the button-head, as is obvious, it, the button-head, is necessarily engaged with and held against being disengaged from the primary-frame by the then overlap of the opposite end-portions of the button-head and their bearing on the under 120 side of said central bar K. And in the making of the fastener described, it would be and is well to have such button-head so shaped, or the under side of said central bar so shaped, or both so shaped, that when the 130

button-head is swung to place it in engagement with the underside of said bar and as the button-head passes into the position of such engagement, there will be a more or less drawing of the secondary-frame toward the primary-frame, and thus a closer bind or hold secured of the secondary-frame on the primary-frame or, with the strap engaged with the bars of the primary-frame, as hereinafter explained, a closer bind or hold thereof to and between the two frames.

In using the fastener described, first place the fastener on the packet in proper position, for instance as shown, Fig. 1, and if the bar E of the fastener is hung as shown, Figs. 2 and 6 more particularly, preferably release its end engaged with the headed-stud Q of the primary-frame, and swing it open. Now loop the strap, intermediate of its length, about the underside and inner edge of the bar E and extend it in opposite directions from said bar, and if said bar E is a swinging one, and has been opened out as has been explained, close it and engage it with the headed-stud Q. Now take the portion of the strap which extends toward the fastener-frame, and pass it over the upper side of the end E, and from thence carry it over the upper side of the packet and down and over the end of the packet toward the bar J, and thence along the under side of the packet, to and up and along the other end of, and over the top of the packet, and loop it over the upper side the round-bar C, and through the slot D in side of and under said bar, and place the remaining free end of the so-looped portion of the strap under the strap and between it and the upper side of the packet, and which, preferably, fasten together these then superimposed layers of the strap, as for instance, by rivets, as shown, Fig. 3, or by a suitable strap-buckle, not shown. This completes the handling or looping of one of the end-portions of the strap, as it was first placed on the bar F, as explained, about the packet and primary-frame, but as will be well to here observe when the encircling and looping of the other and as yet free end-portion of the strap about the packet and the primary-frame and before the secondary-frame P is closed on the primary-frame all as is to be now explained, the looped and encircling end-portion of the strap as has been just described, is to be made taut about the packet and said frame in its said running. Now take the remaining end-portion of the strap, leading loosely from the bar E and pass it over the top of the packet adjacent to said bar and down and over the adjacent side and under the under side and up and over the upper side of the packet and under and up through the slot H adjacent to the inner edge of and over the top of the bar F, on which, draw all the parts of the strap running about the packet and engaged with the pri-

mary-frame taut, and close the secondary-frame P on the primary-frame and secure it as has been explained, whereby as is evident, the strap in all directions of its running will be securely confined to and held on the fastener and to the packet and will be made safe against accidental movement or disturbance from any strain which may come upon it in handling the packet.

To practically release a strap fastened and held as has been explained, it is only necessary to unfasten the cap or cover P from the main frame by swinging its elongated button-head Q so that its longer axis will lie along the longer axis of the central opening L in the cross-piece K of the main frame.

The holding of the strap engaged with the fastener, as has been explained, is by the confinement of the strap practically between the primary-frame, and about the bars of which it was disposed as stated, and the secondary-frame P, and this confinement is substantially the same in effect with all the forms of the primary- and secondary-frames which are shown in the drawings and have been described, except, that it may be said that an additional effect as to the confinement or engagement of the strap on and between the two frames is secured by the necessary interlock of the teeth of the secondary-frame P, Fig. 8, with the strap, as it, the frame P is pressed to its position of confinement on the primary-frame.

If the swinging-arm S is adapted to have a pressing bearing on the strap at the upper side of the cross-bar C of the main-frame, obviously, the strap at such point will be more closely confined to said bar, and further said arm will be safer against accidental displacement in the handling of the packet, etc.

Arranging the bar E of the fastener for being opened out as has been explained is advantageous in that it enables the looping of the strap thereon to be more conveniently done, and avoids the necessity which would otherwise exist, if such bar was fixed and closed, of drawing the strap lengthwise through the opening G of the fastener.

Having thus described my invention what I claim and desire to secure by Letters Patent is,

1. A fastener for straps, comprising two frames, one having, at several of its opposite sides or edges, bars and openings or slots, at and on all of which to loop and engage a strap therewith, and the other, at one side or edge, connected to said strap-receiving frame and adapted to be opened therefrom and closed in relation thereto, in combination with means on said frames relatively adapted to coöperate to secure them together when closed as to each other, and to permit them to be opened from each other.

2. A fastener for straps, comprising two

frames, one having, at several of its opposite sides or edges, bars and openings or slots, at and on all of which to loop or engage a strap therewith, and the other, at one side or edge, 5 connected to said strap-receiving frame and adapted to be opened therefrom and closed in relation thereto, in combination with means on said frame relatively adapted to coöperate to secure them together, when closed as to 10 each other, and to permit them to be opened from each other, and means to operate said means securing said frame together.

3. A fastener for straps, comprising two frames, one having, at several of its opposite 15 sides or edges, bars and openings or slots, at and by all of which to loop and engage a strap therewith, and the other, at one side or edge, connected to said strap-receiving frame and adapted to be opened from and closed upon 20 its said several side-bars, in combination with means on said frames relatively adapted to coöperate to secure them together when closed the one upon said side-bars of the others, and to permit them to be opened 25 from each other.

4. A fastener for straps, comprising two frames, one having, at several of its opposite sides or edges, bars and openings or slots, at and by all of which to loop and engage a 30 strap therewith, and the other, at one side or edge, connected to said strap-receiving frame and adapted to be opened therefrom and closed in relation thereto, in combination with means on said frames, which consist of an elongated and turning button-head 35 on one of said frames, and of an elongated-opening in the other of said frames, the same being relatively located as to each other to permit said button-head to be passed in and 40 out through said opening in closing and opening the frames, and passed in and through said opening to permit said button-head to be then placed across and at its opposite 45 sides of its said opening.

5. A fastener for straps, comprising two frames one having, at several of its opposite sides or edges, bars and openings or slots, at and by all of which to loop and engage a 50 strap therewith, and the other, at one side or edge hinged to said strap-receiving frame, and adapted to be opened therefrom and closed in relation thereto, in combination with means on said frame relatively adapted 55 to coöperate to secure them together when closed as to each other, and to permit them to be opened from each other.

6. A fastener for straps, comprising two frames, one having, at several of its opposite sides or edges, bars and openings or slots, at 60 and by all of which to loop and engage a strap therewith, and the other, at one side or edge, connected to said strap-receiving frame and adapted to be opened therefrom and closed in relation thereto, in combination with means on said frames relatively adapted 65 to coöperate to secure them together when closed as to each other, and to permit them to be opened from each other and with means carried by one of said frames and adapted to operate in connection with said means thereon for securing the frames together and thereby to lock the same against and unlock the same for movement.

7. A fastener for straps, comprising two 75 frames, one having, at several of its opposite sides or edges, bars and openings or slots, at and on all of which to loop and engage a strap therewith, and also having one of said bars attached to the frame to be closed and 80 secured thereto and to be freed and opened therefrom, and the other frame, at one side or edge, connected to said strap-receiving frame and adapted to be opened therefrom and closed in relation thereto, in combination with means on said frames relatively 85 adapted to coöperate to secure them together when closed as to each other, and to permit them to be opened from each other.

8. A fastener for straps, comprising two 90 frames, one having, at several of its opposite sides or edges, bars and openings or slots, at and on all of which to loop and engage a strap therewith, and also having one of said bars at one end hinged to said frame and at the other 95 end together with the frame adapted for the bar to be engaged with and disengaged from the frame and engaged held until released and the other frame, at one side or edge, connected to said strap-receiving frame, and 100 adapted to be opened therefrom and closed in relation thereto, in combination with means on said frames relatively adapted to coöperate to secure them together when closed as to each other, and to permit them 105 to be opened from each other.

In witness whereof, I have hereunto set my hand in the presence of two subscribing witnesses.

WILLIAM H. DAVIDSON.
